UNITED STATES PATENT OFFICE.

JOHN ERDOSY, OF PHILADELPHIA, PENNSYLVANIA.

ATTACHMENT FOR BATHTUBS.

Application filed April 16, 1923. Serial No. 632,240.

To all whom it may concern:

Be it known that I, JOHN ERDOSY, a citizen of the United States, residing at Philadelphia, in the county of Philadelphia and 5 State of Pennsylvania, have invented certain new and useful Improvements in Attachments for Bathtubs, of which the following is a specification.

My invention relates to attachments for 10 bath tubs and its object is to provide means for comfortably supporting a person in the tub above its bottom and for supplying the tub with vapors or heated fluids thereby adapting the tub for use in taking Turkish 15 or other vapor baths.

This object, and other advantageous ends which will be described hereinafter, I attain in the following manner, reference being had to the accompanying drawings in which—

20 Figure 1 is a plan view of a bath tub having my invention applied thereto,

Figure 2 a side view of Figure 1,

Figure 3 a central longitudinal section through Figure 1,

25 Figure 4 a section on line 4—4 of Figure 3,

Figure 5 a perspective view of a reinforcing plate constructed in accordance with my invention,

30 Figure 6 a fragmentary perspective view of the connecting end of one of the fluid conduits,

Figure 7 a central section through the conduits shown in Figure 6 illustrating it connected to the reinforcing plate,

Figure 8 a perspective view of a span connection, and

Figure 9 a perspective view of a supporting hook.

40 Referring to the drawings, 1 indicates a bath tub having the usual turned edge 2. A cover 3 rests on the turned edge and comprises a frame 4 of any suitable character shaped to conform to the edge of the tub and having spans or arches 5 and 6 detachably

45 mounted in supporting clips 5^a and 6^a and spanning the tub from side to side. The supporting clips are secured to the frame 4 in any suitable manner. A cover 7 of flexible

50 sheet material is secured to the frame and spans in any suitable manner. The frame is hinged at 8 and has one of its ends gapped so that a person may enter the tub and lower the cover without it interfering with his head.

55 A bed 9 is composed of tubes 10 connected

to the opposite sides of the bath tub by links 11 and hooks 12 which engage the turned edge of the tub. A perforated sheet 13 is secured to the tubes in any suitable manner 60 and comprises longitudinal strips 14 interwoven with and preferably sewed to transverse strips 15. For the purpose of keeping the cover tightly against the edge of the tub, I connect the spans 5 and 6 to tubes 10 by coiled springs 16 and 16^a in any suitable manner. A head rest 17 is pivoted to the ends of the rods and rests against the turned edge of the tub. A V-shaped opening 18 is provided in the cover adjacent the head rest 70 to permit a person to keep his head from under the cover. For the purpose of making the inner seal for the fluid within the tub, an elastic sheet 19, sewed to the cover to close a part of the opening, is adapted to fit around 75 the neck of the person.

The means for delivering fluid to the tub comprise a reinforcing plate 20 having its edges 21 bent in U-shape to receive the edges 22 of an opening in the flexible sheet 7 and clamp them in place by pressing the legs of the U together or depressing spaced points 23 along its length as shown in Figures 5 and 7. The top and side edges 21 of the plate extend beyond the top of the U part to 80 provide connecting flanges 24. Openings 25 and 26 in the reinforcing plate receive pipes 27 and 28. Pipe 27 is removably connected to a casing 29 which encloses a boiler 30 to which the pipe 28 is removably connected. 90 Any suitable burner 31 may be provided for heating the liquid in the boiler. Pipe 27 carries the heated air from the burner into the tub and pipe 28 carries the vapor, from the fluid in the boiler, into the tub. A conduit 32 is connected to the flanges 24 by hooked flanges 33 at the top and sides thereof. The conduit 32 extends downwardly and inwardly below and under the bed and is preferably covered with a heat insulating material to 100 protect the bather from getting scorched.

The bed is connected to the bath tub by links 11 and hooks 12 as shown in Figures 3 and 4. The hooks, embracing the turned edge, securely hold the bed in position. The head rest 17 bears against the turned edge 2 and thus provides an inclined surface against which a person may comfortably rest his head. The cover is placed on the edge of the tub and its foot end connected to the 110 bed by the coiled springs. The fluid delivery pipes 27 and 28 are placed in holes

25 and 26 in the reinforcing plate and conduit 32 is connected to flange 24 of the reinforcing plate within the tub and extended beneath the bed. The apparatus is then 5 ready for use. A person may now get on the bed and swing the head end of the cover over his body and connect it to the bed by the coiled springs. The elastic or rubber sheet 19 fits snugly around the person's neck and 10 prevents steam from escaping. The vaporized liquid passes through pipe 28 into the tub and the heat from the burner passes through pipe 27. The ends of pipes 27 and 28 lead into the conduit 32 which delivers 15 the vapor and hot air underneath the person on the bed.

When it is desired to put my attachment away in a small space, the pipes 27 and 28 are removed from holes 25 and 26 in the 20 reinforcing plate and the conduit 32 removed from the flanges 24 by sliding it upward off the flanges, it being understood that springs 16 at the head end of the cover, have been disconnected from span 5. 25 Springs 16^a are then disconnected from span 6 and the spans removed from their supporting clips 5^a and 6^a. The cover may then be folded on hinge 8. The bed is disconnected and removed from the tub and the head rest folded on its hinge. The parts 30 may then be placed one on the other and put away into a small space.

While I have described my invention as taking a particular form, it will be understood that the various parts of my invention may be changed without departing from the spirit thereof, and hence I do not limit myself to the precise construction set forth, but consider that I am at liberty to 40 make such changes and alterations as fairly come within the scope of the appended claims.

Having thus described my invention, what I claim as new and desire to secure by Letters Patent is:—

1. In combination with a bath tub; a hinged cover for the tub; a bed supported by the tub; resilient means for connecting the hinged parts of the cover to the bed, and means for delivering fluid through the 50 cover into the tub.

2. In combination with a bath tub; a hinged frame provided with arched spans and resting on the edge of the tub; sheet material on the frame and spans to form a cover for the tub; a bed supported by the tub; springs for connecting the bed to the spans, and means for delivering fluid through the sheet material into the tub.

3. In combination with a bath tub; a hinged cover for the tub; tubes supported by the tub; perforated sheet material connected to the tubes; a head rest hinged to the tubes; springs for connecting the tubes 60 to the hinged parts of the cover, and means

for delivering fluid through the cover into the tub.

4. In combination with a bath tub; a hinged frame conforming to the edge of and resting on the tub; flexible sheet material 70 on the frame to form a cover for the tub; hooks supported by the tub; a bed supported by the hooks; springs connecting the hinged parts of the frame to the bed, and means for delivering fluid through the cover 75 into the tub.

5. In combination with a bath tub; a hinged frame conforming to the edge of and resting on the tub and provided with 80 detachable parts for spanning the tub; flexible sheet material on the frame and spans to form a cover for the tub; hooks supported by the tub; a bed supported by the hooks; springs connecting the spans to the bed, and means for delivering fluid through the sheet 85 material into the tub.

6. In combination with a bath tub; a hinged frame conforming to the edge of and resting on the tub and provided with parts 90 for spanning the tub; flexible sheet material on the frame and spans to form a cover for the tub; hooks supported by the tub; tubes supported by the hooks; longitudinal flexible strips; transverse flexible strips interwoven with the longitudinal strips and connected to the tubes; a head rest hinged to the tubes; springs connecting the spans to the tubes, and means for delivering fluid through the cover into the tub.

7. In combination with a bath tub; a hinged frame conforming to the edge of and resting on the tub and provided with parts 100 for spanning the tub; flexible sheet material on the frame and spans to form a cover for the tub; hooks supported by the tub; links supported by the hooks; tubes supported by the links; longitudinal flexible strips; transverse flexible strips interwoven with the longitudinal strips and connected to the tubes; a head rest hinged to 105 the tubes; springs connecting the spans to the tubes, and means for delivering fluid through the cover into the tub.

8. In combination with a bath tub; a cover for the tub; a plate secured to the cover and having openings; fluid conduits 110 detachably connected to the openings outside of the cover, and a fluid conduit detachably connected to the edge of the plate inside of the cover and leading from the 115 openings into the tub whereby the fluids from the outside conduits will pass down through the inside conduit.

In testimony whereof I have signed my name to this specification in the presence of 120 two subscribing witnesses.

JOHN ERDOSY.
